DRIER FELT

James E. Hooper, Ruxton, Md., assignor to William E. Hooper and Sons Company, Woodberry, Md., a corporation of Maryland

Application January 16, 1937, Serial No. 120,958

6 Claims. (Cl. 24—33)

The invention relates to paper felts or drier felts on which the material is carried forwardly as it progresses from the condition of a pulp being progressively dried or otherwise treated as it advances. Other products including laundry are dried in this way.

The object of the invention is to provide an improved seam or joint construction for drier felts, laundry aprons and the like whereby the paper or pulp sheet or other material being treated is supported out of contact with the clips or other fastening means which join the ends of the felt the protecting means and the portions to which the clips are attached being of the same material integral with and part of the main strip composing the felt or apron.

In the past the ends to be joined have been strengthened by attachment thereto of reinforcing strips of duck or similar materials which are different from the felt in their action on the paper and the absorption of the moisture so that though they are attached to the back of the felt there is a tendency to create a difference in the density and in the nature of the paper web as to the areas which overly the joints. Also the joints of the prior art have been so formed that the ends of the felt which support the paper web near the joint are spaced apart over the clips. These ends become frayed in use and the frayed portions become turned upwardly extending above the web supporting surface, increasing the space between the felt ends so that the clips are exposed permitting the paper or pulp web in more or less moist condition to come into contact with the clips whereby it is permanently marked and discolored and the frayed ends of the felt have a similar action by indenting and thus marking the web in the vicinity of the joint between the ends of the felt.

In accordance with the improved joint construction the adjacent edges of the felt drier ends above the clips are formed by folding the felt material near the joint back upon itself against the back side of the apron or drier felt, the folded edges of the felt being, when the joint is closed, placed in close abutting relation completely closing the supporting surface of the felt at the joint so that they support the paper or pulp above and completely out of contact with the clips, and, by avoiding the presentation of unfinished or exposed edges of the felt at this point, they eliminate fraying so that the closure is permanent. The paper is not only protected from contact with the clips and consequent marking and discoloration but is also protected from marking and in-

dentation by the frayed edges, as in the prior construction.

In accordance with the preferred form of the invention, the folds which are thus abutted to form the juncture of the supporting surfaces of the two sections of felt being joined are actually spaced back from the extreme end edges of the felt being joined and these end portions beyond the first mentioned folds are turned or folded forwardly under or back of the felt or apron. The multiple folds formed in each felt end are then secured together by riveting, stapling, sewing or cementing and the clips are attached to these last mentioned forwardly folded ends beneath or back of the folds or flaps first mentioned as forming the abutting edges of the two sections of felt at the paper supporting surfaces.

The end edges to which the clips are attached may either be doubled by folding and then secured or may be single and if desired treated by impregnation with resinous compounds, bakelite or the like. The abutting folds forming the meeting ends of the felt at the top surface may be either over and in line with the clips or other joint or spaced away from the clips by shortening the fold on one end and lengthening the fold on the other end thus further protecting the paper from contact with the clips or it may be located in its relation to the clips as desired.

In addition to forming a completely and permanently closed joint at the web supporting surface which joint except for the fastening clips or the like is composed of the same uniform material composing the remainder of the felt, avoiding any variation of action in the different parts of the felt, the improved construction has the advantage of greatly improved protection of the paper from the clips, extreme durability preventing fraying of the ends and marking the paper or opening of the joint and the improved construction has the further advantage that thus formed by folding the integral edge portions of felt and fastening by riveting, stapling, sewing or cementing, the joint is formed more quickly and more cheaply than by the addition of reinforcing strips, also the formation of these edge contacting and joint attaching folds of the same material integral with the remainder of the felt makes it easy by using the weave lines as a guide to form more quickly a straight joint at right angles to the selvage edges at the sides than by the old method of attached reinforce and these integral attaching and contact folds have the further advantage that they pull uniformly and keep the belt straight under tension. The new

construction also has the advantage that the clips are attached directly to the edges of the felt or apron material instead of to a separate attached reinforce so that there can be no breaking of the belt due to shearing of the reinforce.

It is a further advantage of the invention that the better quality belts being provided with an asbestos ply for engagement with the paper which contacts the heating drums, the attaching fold 10 contains an asbestos ply where the clips are attached so that it affords permanent resistance to overheating and there is no danger of pulling the clips from the fabric on this account.

In the accompanying drawings, I have illustrated two forms of joint embodying the invention.

Figure 1 is a plan view of the felt or apron at and adjacent the joint looking from the paper web supporting side.

20 Figure 2 is a similar view of the joint and adjacent portions of the felt or apron looking at the same from the opposite side to Figure 1.

Figure 3 is a section on the line 3, 3 in Figure 1 in which the protecting flaps or pleats contact on 25 a line directly over the clips.

Figure 4 is a section on the same line showing substantially the same form of joint in which the protecting flaps or folds which support the material out of contact with the clips abut or meet 30 on a line spaced away from the clips.

Figure 5 is a section similar to Figure 4, the arrangement being slightly different in that the ends of the felt to which the clips are attached instead of being doubled are of a single thickness 35 and may be treated by impregnation to prevent pulling of the clips.

Figure 6 is a bottom plan view of the joint Figure 5.

Referring to the drawings by numerals each of 40 which is used to indicate the same or similar parts in the different figures the construction Figures 1, 2 and 3 comprises felt or similar material 1 composing the drier felt or apron 2. This felt particularly when used in the manufacture of 45 paper is preferably provided with a web engaging or upper ply 4 of asbestos the lower ply 3 being of cotton, wool or other suitable textile fiber. The asbestos may be omitted from paper felts as well as other dryer aprons. Two end 50 portions 5 and 6 of this drier felt or apron are shown as connected by a joint 7. In this form of joint the end portions to which the clips 8 are attached are folded forming clip supporting edges 9 to which the clips 8 or other fastenings 55 are attached in any suitable manner. Inwardly of the felt ends in the direction of their length the felt end portions 5, 6 are again folded forming protecting flaps or pleats 10 and 10' which when the clips 8 are attached have their bends forced 60 into close contact at 11. Beyond the folds 10, the folded clip supporting edges 9 are also folded forwardly toward the joint forming a fold at 13 and the multiple thicknesses of material resulting 65 from the three folds which may be formed in any convenient order or sequence are fastened together backwardly of the clips by riveting, stitching or stapling at 12 or they may if desired be cemented for this purpose. The word clip is 70 used to designate any suitable end fastening.

Figure 4 shows a fold 14 corresponding to the fold 10 of increased width and the fold 15 corresponding to the fold 10' of decreased width displacing the line of contact 16 to the right so that 75 it is spaced away from the clips 8 or other fas-

tenings the other features of this construction being similar to that of Figures 1, 2 and 3.

The construction of Figure 5 is similar to that of Figure 4 except that the clip supporting ends 18 instead of being folded as at 9, 9 and hence 5 doubled are of a single thickness being preferably toughened by impregnating with suitable material of a resinous nature or bakelite or the like at 18'. In this construction, Figure 5, the two folds or pleats provide three thicknesses of the 10 material 19, 20 and 21 secured in any suitable manner as previously described. The heat resisting material as asbestos when used is believed to give better protection from heating and to assist in avoiding any tendency to loosen the clips 15 8 on account of such heating.

Without regard to the nature of the material of which the felt or apron is made, it is of importance that while the paper web or other product being treated is fully protected from the clips 20 by the contacting folds substantially in the supporting surface of the felt or apron and formed integrally therewith of the same piece of material, the attaching portions, to which the clips are secured beneath said folds, may be part of the 25 integral felt or apron and not subject to separation from the apron by shearing as when separate strips are attached to the back of the apron for this purpose.

The joint construction shown by the provision 30 of folded edges of the felt material, folded edges of the adjacent sections of felt being in close contact, said folds being relatively resilient thus maintaining the contact after long use, afford a permanent support for the paper or other material out of contact with the clips or other joint mechanism and these folds or folded flaps being composed of continuous integral portions of fabric not subject to fraying and therefore do not mark or indent the paper material and they retain their 40 initial condition and close contact after an indefinitely long period of use without any tendency to fray.

It is of further advantage that the folds or flaps forming the joint being formed by folding 45 and fastening the integral fabric comprising the felt or apron, the joint is much more easily and cheaply formed, is easier to align and much less apt to get out of alignment than when formed of separate reinforcement strips or parts, the lines 50 of the weave being helpful in making a true joint at right angles to the selvage edges 25 of the sides. It is also found that the end flaps and the folds being of the same material as the felt have the same effect on the paper web as does the 55 remainder of the felt avoiding any lack of uniformity incident to the use of any other reinforce.

I have thus described an integral fold and protected joint for paper felts, laundry aprons and the like embodying the features of the invention, the description being specific and in detail in order that the manner of constructing, applying, operating and using the invention may be fully understood, however, the specific terms herein are used descriptively rather than in a 65 limiting sense, the scope of the invention being defined in the claims.

What I claim as new and desire to secure by Letters Patent is:

1. A dryer felt or apron having a joint comprising two integral end portions of the material composing the felt attached to which end portions are detachable means for joining the ends of the drier felt to close said joint, an integrally woven portion of the felt material on each side 70 75

5 of said joint and adjacent each of said ends being folded upon itself and fastening means securing said folds to said end portions the bends of the folds on each side of the joint being in closely abutted relation substantially in the supporting surface of the felt closing the supporting surface of the felt when the joint is closed by the said detachable means.

10 2. A paper felt joint comprising adjacent ends of said felt and belt fastening means for joining said ends the joint also comprising folded portions on each side of said joint, said folded portions being composed of the felt material integral and continuous with the remainder of the felt and having supporting surfaces substantially 15 flush with the supporting surfaces of the main felt and having the bends of said folds on the respective ends of said felt and on the opposite sides of said joint in close abutting relation when 20 the joint is closed the felt material on each side of the joint being further folded on the back side of said felt, the multiple folds of each felt end being secured together and the belt fastening means being secured to said back folds.

25 3. A fabric drier apron having a joint connecting two ends of said apron said joint comprising a fold on each side of said joint, said folds being formed of the apron fabric and woven integrally with the remainder of the apron 30 fabric, the bends of the folds abutting substantially in the supporting surface of the apron, portions of said fabric beyond said first mentioned folds being folded toward the plane of said meeting bends, and overlying said first mentioned folds on the back side of the apron, said latter folded portion being further folded to 35 double thickness and having cooperating fastening means for said respective ends attached thereto.

40 4. A fabric drier apron having a joint con-

necting two ends of said apron said joint comprising a fold on each side of said joint, said folds being formed of the apron fabric and integral with the remainder of the fabric, the bends of the respective folds abutting in close contact substantially in the supporting surface of the apron, the edge portions of said fabric beyond said first mentioned folds being folded toward the plane of said bends beneath said first mentioned folds and having cooperating fastening means for said respective ends attached thereto, and covered by said first mentioned folds, the fabric being impregnated to prevent loosening of the fastening means and the respective folds on each side of the joint having securing means for retaining the folds in fixed relation.

5 5. A fabric drier apron for paper or the like having a joint comprising folded portions of the apron fabric integral therewith on each side of the joint, the bends of the folds meeting substantially in the supporting plane of the apron, said folds being secured and having additional means attached to each fold on the side remote from said supporting surface and fastening members for the joint secured to said means.

20 6. A fabric drier apron for paper or the like having a joint comprising folded portions of the apron fabric woven integrally with the fabric of said apron on each side of said joint, the bends of the folds meeting substantially in the supporting surface of the apron when the joint is closed said folds being respectively secured and having additional means secured to each fold on the side remote from said supporting surface and fastening members for the joint secured to said 30 means, the line of contact of said abutting bends of the folds being spaced away from said fastening means in the direction of the length of said apron.
